(57) **CLAIM**

The ornamental design for a cable box device including a touch screen display with a retractable cover, as shown and described.

DESCRIPTION

FIG. 1 is a front perspective of the cable box device including a touch screen display with the retractable cover in a closed position.

FIG. 2 is a right side perspective of the cable box device including a touch screen display with the retractable cover in a closed position.

FIG. 3 is a top plan view of the cable box device including a touch screen display with the retractable cover in a closed position.

FIG. 4 is a bottom plan view of the cable box device including a touch screen display with retractable cover.

FIG. 5 is a front view of the cable box device including a touch screen display with retractable cover.

FIG. 6 is a right side view of the cable box device including a touch screen display with retractable cover.

FIG. 7 is a left side view of the cable box device including a touch screen display with retractable cover.

FIG. 8 is a bottom perspective view of the cable box device including a touch screen display with retractable cover.

FIG. 9 is a top perspective of the cable box device including a touch screen display with the retractable cover in a partially open position.

FIG. 10 is a left side view of the cable box device including a touch screen display with the retractable cover in a partially open position.

FIG. 11 is a top plan view of the cable box device including a touch screen display with the retractable cover in a partially open position.

FIG. 12 is a top perspective view of the cable box device including a touch screen display with the retractable cover in a fully retracted position.

FIG. 13 is a right side view of the cable box device including a touch screen display with the retractable cover in a fully retracted position; and,

FIG. 14 is a top plan view of the cable box device including a touch screen display with the retractable cover in a fully retracted position.
